[57] **CLAIM**

The ornamental design for a seat, as shown and described.

DESCRIPTION

FIG. 1 is a perspective view of a seat showing my new design;

FIG. 2 is a front elevational view thereof;

FIG. 3 is a top plan view thereof;

FIG. 4 is a right side view thereof, the opposite side being a mirror image of the side shown;

FIG. 5 is a perspective view of a second embodiment thereof in the form of a love seat which differs from the first embodiment shown in FIG. 1 only in length; and,

FIG. 6 is a perspective view of a third embodiment thereof in the form of a chair which differs from the first and second embodiments shown in FIGS. 1 and 5 only in length.

The rear of the seat is not part of the claimed design.
